GRATE

Frederick D. Conard, Philadelphia, Pa.

Application December 26, 1931
Serial No. 583,296

2 Claims. (Cl. 126—152)

This invention relates to grates, and has for an object to provide a grate for supporting a fire in a stove, furnace, or the like, and having improved features for folding the grate for inserting and withdrawing.

5 A further object of the invention is to provide a grate having hinges located upon the under side along a diametrical line, which diametrical line forms the abutting of the two sections of the grate.

10 A further object of the invention is to provide a grate divided into halves, each half being provided with hinge members identical in both halves, and reversible to coact with the hinge members on the other half.

15 The invention therefore comprises a grate having grate bars spaced apart for the support of fuel and the introduction of air, two of said grate bars abutting against each other at a median line, with hinges formed as corresponding and identical members upon the undersides of the grate bar sections serving to hinge the grate so that it may be folded into one-half its original width.

20 The drawing illustrates an embodiment of the invention and the views therein are as follows:

Figure 1 is an inverted plan view of the grate,

Figure 2 is a view of the grate in edge elevation, as indicated by arrow 2 at Figure 1, and

25 Figure 3 is an edge view of the grate folded.

Like characters of reference indicate corresponding parts throughout the several views.

The grate of the present invention is intended to be exemplified in a circular grate, indicated at 10, although it is to be understood that it may apply to grates other than circular. The grate is provided with substantially the usual and ordinary grate bars 11, with the intervening spaces for the introduction of air, and the passage of ash.

30 The grate bars which extend substantially diametrical of the grate, are indicated as 12, the halves of the bars 12 being identical. The bars are each provided with hinge members 13 at one end and 14 at the opposite end, so arranged that each will co-act with the other.

35 A pintle 15 completes the hinge and the completion of the hinge completes the grate as a unitary structure. In operative position, as supporting a fire, it will be as shown at Figures 1 and 2, that is to say, extended to its full width. For the purpose of inserting or withdrawing, for instance through a fire door, the grate may be folded as shown at Figure 3 so that it will occupy a lesser area.

40 The grate, while adapted for general use, is

more particularly intended as a repair grate, or a replacement grate, or applying to a heating unit for the support of fuel of different grade or size. As an example, the grate of a heating unit might be such as to properly support that size of 60 coal known as "egg". For the purpose of fitting the heating unit, to employ a smaller size, as for instance "buckwheat" which is a cheaper fuel, this replacement or supporting grate, here illustrated, will be employed with the bars properly 65 spaced for the purpose. By folding the grate as shown, it is possible to insert or withdraw it through the fire or stroke door without tearing the heating unit apart.

Of course, the grate, herein illustrated, may be 70 modified and changed in various ways without departing from the invention herein set forth and hereinafter claimed.

The invention is hereby claimed as follows:

1. A grate comprising two approximately identical sections, each having one straight edge, each section having hinge-ears formed upon its under side at said straight edge, the ear adjacent one end being spaced farther from the perimeter than the ear at the other end, said ears 80 of the sections being so relatively positioned that when mated they maintain the united sections in a symmetrical unit.

2. A grate comprising two approximately identical semi-circular sections, each section having hinge-ears formed upon its under side, the ear adjacent one end being spaced farther from the perimeter than the ear at the other end, said ears 85 of the sections being so relatively positioned that when mated they maintain the united sections in 90 a circular unit, and diametrical bars abutting to maintain planarity of the grate surface opposite the ears.

FREDERICK D. CONARD.
